UNITED STATES PATENT OFFICE.

ERASTUS A. BISHOP, OF WALLOWA, OREGON.

SPARK-ARRESTER.

971,823.

Specification of Letters Patent.

Patented Oct. 4, 1910.

Application filed June 2, 1909. Serial No. 499,622.

To all whom it may concern:

Be it known that I, ERASTUS A. BISHOP, a citizen of the United States, residing at Wallowa, in the county of Wallowa, State of Oregon, have invented certain new and useful Improvements in Spark-Arresters; and I do hereby declare the following to be a full, clear, and exact description of the invention, such as will enable others skilled in the art to which it appertains to make and use the same.

This invention relates to spark arrester attachments for smoke stacks, and has for its object to improve the construction and increase the efficiency and utility of devices of this character.

With this and other objects in view, the invention consists in certain novel features of construction as hereafter shown and described and then specifically pointed out in the claim, and in the drawings illustrative of the preferred embodiment of the invention, Figure 1 is a side elevation of the improved device attached to a portion of a smoke stack. Fig. 2 is a plan view of the same. Fig. 3 is a section on the line 3—3 of Fig. 2.

The improved device comprises a tubular member adapted to be attached to the discharge end of the smoke stack, a portion of a smoke stack being represented at 10. The tubular member is formed of a slightly inclined body 11 having a curved portion 12, the latter terminating in a downwardly directed portion 13 which engages the smoke stack 10. The forward portion of the body 11 is contracted as shown at 14, the lower side 15 of the contracted portion conforming to the general incline of the body and in 40 longitudinal alignment therewith, while the upper portion 16 is inclined more sharply, as shown, whereby a relatively contracted downwardly inclined nozzle is produced at the discharge end of the body.

Rising from the body 11 near its juncture with the contracted portion is a relatively large outlet 17. The sides of the outlet being vertical and forming continuations of the sides of the body 11. The width of the body 50 11 thus equals the total width of the outlet portion 17, as will be obvious. At its forward side the outlet portion 17 is inclined inwardly as shown at 18, while a forwardly inclined deflector or reflector 19 is arranged 55 to extend transversely of the interior of the body 11, and in the path of the products of

the combustion which pass through the device.

With a device thus constructed and supported upon the smoke stack, the products 60 of the combustion as they rise from the stack are directed laterally by the curved portion 12 and come in contact with the downwardly inclined deflector or reflector 19, and are thereby thrown to the bottom of 65 the body 11 and from whence they are removed over the inclined lower side of the body by the continued action of the draft. The products of the combustion then pass through the body 11 into the contracted discharge 14, and are checked and retarded 70 thereby thus giving the heavier particles of the products, such as cinders and the like an opportunity to settle into the bottom of 75 the body, while lighter gases and smoke only pass through the discharge 17 and the nozzle. The cinders and heavier particles of the products of the combustion are thus checked and permitted to settle in the body 11 and are discharged through the nozzle 80 14 and fall to the ground therefrom, while the gases and the smoke only pass through the discharge 17. The force of the discharge causes the cinders to be carried through the nozzle, but in a horizontal 85 direction, so that they do not rise above the stack, and the danger therefrom is thereby eliminated. The curved portion 12 and the reflecting member 19 do not materially interfere with the draft of the smoke stack, 90 while at the same time checking the progress of the products of the combustion and retarding them so that the cinders and coarser particles may be separated as before described.

The improved device is simple in construction, can be adapted to stacks of various kinds, but is more particularly designed for use in connection with factories in which the lighter grades of fuel are employed, and 100 wherein greater quantities of cinders and other dangerous and deleterious matter is thrown off during the operations of the generators.

The improved device is especially adaptable for use in connection with saw-mills and like manufactories wherein saw-dust and similar material is employed as fuel.

What is claimed is:—

The herein described spark arrester comprising a pipe having a downwardly inclined arm contracted and open at its rear

end and a downwardly curved elbow at the front end of said arm for attachment to the upper end of a smoke stack, said elbow closing the front end of said arm against the admission of air, said arm being further provided on its upper side, at a point intermediate its ends, with an upwardly extending smoke discharge arm, the rear side of which is upwardly inclined to form a baffle and to contract the upper end of said discharge arm, and a downwardly and rear-

wardly inclined discharge deflecting baffle in the upper side of the said inclined arm and extending partially across the lower end of said smoke stack discharge arm. 15

In testimony whereof, I affix my signature, in presence of two witnesses.

ERASTUS A. BISHOP.
